SAFETY STOP FOR VEHICLE LIFTS

James M. Cunneen, Jersey City, N. J.

Application April 15, 1930. Serial No. 444,626

20 Claims. (Cl. 254—89)

My invention relates to vehicle lifts and has for an object to provide safety means for retaining a vehicle on the lift.

My invention is particularly applicable to lifts 5 of the type used in garages or service stations in which an automobile is run upon the lift while the latter is lowered and then the lift is raised to provide access to under parts of the car.

It is customary to provide such lifts with chocks 10 which are applied thereto after the car has been run on the lift to prevent it from sliding off. These chocks or car stops are manually set and sometimes a careless operator forgets to apply the chocks or else he sets them improperly so 15 that there is danger that the car may slide off when the lift is raised off the ground.

An object of my invention is to provide a chock which will be automatic in its operation, moving into stopping position when the lift is 20 raised and moving to clear-position when the lift is lowered to the ground.

Another object of the invention is to provide an approach hinged to a lift in such manner that when the lift is lowered it will serve to guide the wheels of a car running upon the lift and when the lift is raised will tilt to present stops 25 for the wheels.

Another object is to provide means for adjusting the approach members so as to allow for an 30 uneven floor.

Another object of the invention is to provide a structure in which water will not collect to 35 freeze and render the parts inoperative.

Another object of the invention is to provide 40 a safety stop and approach which may be readily attached to existing lifts.

Other objects of the invention will appear in the following description of a preferred embodiment and thereafter the novelty of the invention 45 will be pointed out in the claims.

In the accompanying drawing;

Figure 1 is a view in side elevation of a lift equipped with my improved safety stop;

Fig. 2 is a view in section taken substantially 50 on the line 2—2 of Fig. 6 showing the manner of attaching the safety stop and approach to a lift and also showing the position of the parts when resting on the ground;

Fig. 3 is a similar view showing the position 55 of the parts when the lift is raised off the ground;

Fig. 4 is a view in transverse section taken on the line 4—4 of Fig. 2;

Fig. 5 is a view in transverse section taken on 60 the line 5—5 of Fig. 3; and

Fig. 6 is a fragmentary plan view of the safety stop applied to a lift.

Referring particularly to Fig. 1, I show a conventional automobile lift of a type comprising 65 channel beams 10 supported on a plunger 11.

Means (not shown) are provided for operating the plunger to raise and lower the lift. It will be understood that there are two channel beams 10, one for the wheels on the right hand side of the car and the other for the wheels on the 65 left hand side of the car. In the particular form of lift illustrated, the beams 10 comprise a horizontal web 12 and a pair of opposite side flanges 13. In some forms of lifts, however, the flange 13 on one side is omitted or else is much lower than 70 the flange on the other side of the beam. My safety stop device is applicable to either type of lift and it will be understood that one of these safety devices may be applied to each end of 75 each channel beam.

My invention includes a bracket formed with a pair of arms 14 which are secured to the under side of the web portion 12 of the channel beam. These arms are preferably channel-shaped, as shown in Fig. 5, and are secured to the beam 10 80 by means of bolts 15. The arms 14 project from a cross-bar 16 whose upper face lies flush with the upper surface of the channel web 12. Projecting outward from the cross-bar 16 are two arms 17 which are preferably connected by a cross brace 18 near their outer ends, and provide bearings 85 for a hinge pin 19.

A chock member 20 which is of channel-shaped form, as shown clearly in Fig. 4, is hinged to the arms 17, being provided with depending hinge lugs 90 21 which are journaled on the pin 19. The under face of the chock 20 is formed with ribs 22 of V-shaped section which rest on the arms 17 when the chock is in the lowered position, so that there is no broad contact of the chock with said arms. 95 The advantage of this arrangement will be pointed out hereinafter.

Projecting laterally from the arms 17 are lugs 23 which are adapted to engage inward extensions or heels 24 of the lugs 21 when the chock is in the 100 raised position shown in Fig. 3, thus limiting the extent to which the chock can be raised.

An approach member 25 is also hinged to the arms 17, being provided with hinge lugs 25a journaled on the pin 19. The member 25 is of channel-shaped section with the side flanges thereof flaring outwardly toward the outer end of the member, as clearly shown in Fig. 6. Each lug 21 is provided with an outwardly extending toe portion 26 which is provided with a set screw 27 110 adapted normally to engage the under surface of the approach member 25.

A link 28 is hinged to the underside of the chock 20 and extends through an opening 29 formed in the cross bar 16. The free end of the 115 link 28 is formed with a cross bar 30 adapted to engage the bar 16 when the chock is in the raised position shown in Fig. 3.

When the lift is in lowered position, the bar 16, and arms 17 will rest on the floor or ground and 120

the parts will assume the position shown in Fig. 2. It will be observed that the web portion of the chock lies flush with the upper surface of the cross-bar 16 and the web of the channel beam 5 10. The approach member 25 assumes an inclined position, as shown, the angle of which will depend on the evenness of the floor. The set screws 27 are adjusted to bear snugly against the under face of the approach member when resting 10 on the floor. When the parts are in the position shown in Fig. 2 they provide an easy approach from the ground level to the channel beams, so that a car may readily be run up on the lift. As 15 shown in Fig. 6, the side flanges of the chock are aligned with the said flanges of the channel beam and the side flanges of the approach member are aligned at their inner ends with the side flanges of the chock. If desired, however, one of the side flanges of the chock and also of the approach 20 may be omitted or materially reduced in height. The approach member 25 is made heavier than the chock 20 so that when the lift is raised off the ground the chock will tilt to the position shown in Fig. 3. In this position, the chock will prevent 25 the wheels of a car from rolling off the lift. While a certain amount of the strain on the chock is taken by engagement of the heels 24 with the lugs 23 most of the strain is taken by the link 17 whose cross bar 30 bears against the inner 30 face of the bar 16.

It will be observed that the chocks come into position automatically, owing to the weight of the approach members 25 which bear against the set screws 27. When the lift is lowered, the approach members will be supported by the ground or floor, permitting the chocks to drop by gravity to the position shown in Fig. 2, so that the car may be run off either end of the lift. While the approach members are being turned by engagement with the ground, from the position shown in Fig. 3 to that shown in Fig. 2, their forward edges will slide along the ground and for this reason said edges are rounded, as indicated at 31 in Fig. 2.

It will be noted that a small space 32 is provided between the inner edge of the chock and the cross-bar 16, the purpose of which is to prevent water from collecting at this joint and freezing so as to hold the chock in lowered position. For 40 the same reason, the chock does not lie flat upon the arms 17 but has line contact with said arms by reason of the V-shaped webs 22, so that there will be a minimum of surface which could be frozen fast to the arms 17. The bracket extending outwardly from the cross-beam 16 is an 45 open frame work in which no water can collect, thus precluding the danger of having the parts freeze fast.

It will be observed that the safety stops are entirely automatic in their operation and do not 50 depend upon the attention of an operator, thereby overcoming a serious defect of safety stops as heretofore provided.

The member 20 serves a dual purpose: When 55 raised it acts as a stop or chock, and when lowered it serves as a guide for the vehicle wheels, being virtually a continuation of the approach member 25. The members 20 and 25 may be integrally connected but I prefer to provide a 60 hinged connection between them so that in lowered position the member 25 may adjust itself to any unevenness of the floor without disturbing the position of member 20 which should preferably lie flush with the web 12 of the channel beam.

75 It will be understood that my safety stop is ap-

plicable not only to the particular form of lift shown in the drawing, but also to other forms of lifts or elevators. I wish it to be understood, therefore, that the drawing is illustrative and not limitative of my invention and that I am at 80 liberty to make such changes in form, construction and arrangement of parts as fall within the spirit and scope of the following claims.

I claim:

1. In combination with a vehicle lift, a chock 85 pivotally mounted at one end of the lift and normally lying flush with the lift, a counterbalance connected to the chock and normally resting on the ground, said counterbalance operating when the lift is raised to tilt the chock into operative 90 position.

2. In combination with a vehicle lift, an approach member pivotally mounted at one end of the lift and adapted to rest at its outer end on the ground when the lift is in lowered position, and 95 an extension of said approach member adapted to swing upward to form a vehicle stop when the lift is raised.

3. In combination with a vehicle lift, a chock pivotally mounted at one end of the lift and normally lying flush with the lift, a weight connected 100 to the chock and normally resting on the ground, said weight operating when the lift is raised to tilt the chock into operative position, and a stop to limit the tilting of the chock. 105

4. In combination with a vehicle lift, a chock pivotally mounted at one end of the lift and normally lying flush with the lift, a weight connected to the chock and normally resting on the ground, said weight operating when the lift is 110 raised to tilt the chock into operative position, and means carried by the chock for limiting the extent to which the chock may be tilted. 115

5. In combination with a vehicle lift, a safety stop comprising an approach member pivoted to 115 one end of the lift, a chock pivotally connected to the approach member, the approach member being heavier than the chock and normally resting on its outer edge on the ground when the lift is in lowered position, the chock forming a continuation of the approach member and normally lying in lowered inoperative position, and a connection between the chock and the approach member whereby the chock will be lifted by the weight of the approach member into chocking 125 position when the lift is raised. 120

6. In combination with a vehicle lift, a safety stop comprising an approach member pivoted to one end of the lift and a chock pivotally connected to the approach member, the approach member 130 being heavier than the chock and normally resting on its outer end on the ground when the lift is in lowered position, the chock forming a continuation of the approach member and normally lying in lowered inoperative position, a connection 135 between the chock and the approach member whereby the chock will be lifted by the weight of the approach member into chocking position when the lift is raised, and means for adjusting the connection between the approach member and 140 the chock. 145

7. A stop device for a vehicle lift, comprising a bracket adapted to be secured to one end of the lift, a transverse hinge pin carried by the bracket, a chock hinged upon said pin and extending inward toward the lift, an approach member also hinged upon the pin and extending outward, the approach member being heavier than the chock member and normally resting on the ground when the lift is in lowered position, 150

and cooperative means on the chock and the approach whereby when the lift is raised the chock will be raised to operative position by the weight of the approach member.

5. A stop device for a vehicle lift, comprising a bracket adapted to be secured to one end of the lift, a transverse hinge pin carried by the bracket, a chock hinged upon said pin and extending inward toward the lift, the chock when in normal position lying flush with the lift, an approach member also hinged upon the pin and extending outward, the approach member being heavier than the chock member and normally resting on the ground when the lift is in lowered position, and cooperative means on the chock and the approach whereby when the lift is raised the chock will be raised to chocking position by the weight of the approach member.

8. A stop device for a vehicle lift, comprising a bracket adapted to be secured to the lift and formed with outwardly projecting arms, a chock normally lying on said arms and hinged to the outer ends of the arms, and an approach member also hinged to the outer ends of the arms, the chock member being formed with an outward extension adapted to bear against the under face of the approach member, the approach member being heavier than the chock whereby when the lift is raised the chock will be tilted to chocking position by the weight of the approach member.

9. A stop device for a vehicle lift, comprising a bracket adapted to be secured to the lift and formed with outwardly projecting arms, a chock normally lying on said arms and hinged to the outer ends of the arms, an approach member also hinged to the outer ends of the arms, the chock being formed with an outward extension, and an adjustable support between said extension and the under face of the approach member, the approach member being heavier than the chock whereby when the lift is raised the chock will be tilted to chocking position by the weight of the approach member.

10. A stop device for a vehicle lift, comprising a bracket adapted to be secured to the lift and formed with outwardly projecting arms, a chock normally lying on said arms and hinged to the outer ends of the arms, an approach member also hinged to the outer ends of the arms, the chock being formed with an outward extension, and an adjustable support between said extension and the under face of the approach member, the approach member being heavier than the chock whereby when the lift is raised the chock will be tilted to chocking position by the weight of the approach member.

11. A stop device for a vehicle lift, comprising a bracket adapted to be attached to the end of the lift, said bracket being formed with outwardly extending arms, a chock formed on its under face with ribs adapted normally to rest upon said arms, the chock being pivotally connected at its outer end to the arms, an approach member heavier than the chock and also pivotally connected to the arms, and means connecting the chock and the approach whereby when the lift is raised the chock will be raised to chocking position by the weight of the approach member.

12. A stop device for a vehicle lift, comprising a bracket adapted to be attached to the end of the lift, said bracket being formed with outwardly extending arms, a chock formed on its under face with ribs adapted normally to rest upon said arms, the chock being pivotally connected at its outer end to the arms, an approach member heavier than the chock and also pivotally connected to the arms, means connecting the chock and the approach whereby when the lift is raised the chock will be raised to chocking position by the weight of the approach, a link connected at one end to the chock, the bracket being formed with an opening through which the link passes, and a cross head on the other end of the link to engage the bracket and limit the extent to which the chock may be raised.

13. A stop device for vehicle lift, comprising a bracket adapted to be attached to one end of the lift, a chock member normally resting on the bracket and hinged thereto at its outer end, a weight connected to the chock and normally supported by the ground, said weight serving to tilt the chock into chocking position when the lift is raised, the bracket being formed with an aperture, and a brace rod passing through the aperture and connected at one end to the chock, the opposite end of the brace rod being formed with a head to engage the bracket and limit the extent to which the chock may be tilted.

14. In combination with a vehicle lift, a safety stop comprising an approach member pivoted to one end of the lift, a chock pivotally connected to the approach member, the approach member being heavier than the chock and normally resting on its outer edge on the ground when the lift is in lowered position, said outer edge of the approach member being rounded, the chock forming a continuation of the approach member and normally lying in lowered inoperative position, and a connection between the chock and the approach member whereby the chock will be lifted by the weight of the approach member into chocking position when the lift is raised.

15. The combination of an elevating platform, a ramp hinged thereto, a pivoted chocking device, mechanism connecting the chocking device with the ramp to swing the chocking device on its pivot when the ramp changes its angular relation to the platform.

16. The combination of an automobile lift having runways, ramps for the ends thereof, hinge means pivotally connecting the ramps to the runways, recesses being provided between the ramps and the ends of the respective runways above said hinge means, and a chock member having means supporting it to swing from a position in said recess to a position above the level of the runways.

17. The combination of an automobile lift having a runway, a chock pivotally mounted at one end of the runway on an axis transverse to that of the runway and normally lying in inoperative position when the lift is lowered, and means tending to tilt the chock to chocking position when the lift is raised.

18. The combination of an automobile lift having a runway, a chock pivotally mounted at each end of the runway on an axis transverse to that of the runway, each chock normally lying in inoperative position when the lift is in lowered position, and means tending to tilt each chock to chocking position when the lift is raised.

19. The combination of an automobile lift having a runway, a ramp at an end of the runway relatively movable with respect to the runway, a chocking device normally in inoperative position when the lift is in lowered position, and means interconnecting the ramp and the chocking device for moving the latter into chocking position when the lift is raised.

20. The combination of an automobile lift having a runway, a ramp at each end of the runway and relatively movable with respect to the runway, a chocking device at each end of the ramp, said device lying normally in inoperative position when the lift is in lowered position, and means interconnecting the ramps and the chocking devices for moving the chocking devices into chocking position when the lift is raised.

JAMES M. CUNNEEN.
